CLAIM

I claim the ornamental design for a faucet, as shown and described.

DESCRIPTION

FIG. 1 is a perspective view of the claimed design;

FIG. 2 is a front view thereof;

FIG. 3 is a rear view thereof;

FIG. 4 is a right side view thereof;

FIG. 5 is a left side view thereof;

FIG. 6 is a bottom view thereof; and,

FIG. 7 is a top view thereof.

The ornamental design that is claimed is shown in solid lines in the figures. Broken lines of equal or substantially equal length dashes in the drawings are for illustrative purposes only and form no part of the claimed design. Broken lines formed by equal length dashes show unclaimed portions of the design. Broken lines formed of unequal length dashes (i.e. dash-dot) show boundaries between claimed and unclaimed portions of the design. Broken lines having a jagged element show that no particular length of the portion is claimed.
